Specification for Design.

Patented May 4, 1920.

Application filed September 15, 1919. Serial No. 324,051. Term of patent 3½ years.

To all whom it may concern:

Be it known that I, MORRIS H. J. MASONOFF, a citizen of the United States, residing at Kansas City, in the county of Jackson and State of Missouri, have invented a new, original, and ornamental Design for a Housing for Spark-Intensifiers, of which the following is a specification, reference being had to the accompanying drawing, forming part thereof.

Figure 1 is a perspective view of a housing for a spark intensifier, showing my new design.

Fig. 2 is an elevation of the same, and Fig. 3 is a cross section thereof.

I claim—

The ornamental design for a housing for a spark intensifier, as shown.
